(57) **CLAIM**

I claim the ornamental design for a glow-in-the-dark toy fire hat, as shown and described.

DESCRIPTION

FIG. 1 is a top plan view of a glow-in-the-dark toy fire hat embodying the design of the present invention;

FIG. 2 is a bottom plan view of the glow-in-the-dark toy fire hat of FIG. 1;

FIG. 3 is a front elevation view of the glow-in-the-dark toy fire hat of FIG. 1;

FIG. 4 is a right side elevation view of the glow-in-the-dark toy fire hat of FIG. 1;

FIG. 5 is a left side elevation view of the glow-in-the-dark toy fire hat of FIG. 1;

FIG. 6 is a rear elevation view of the glow-in-the-dark toy fire hat of FIG. 1;

FIG. 7 is a left front side perspective view of the glow-in-the-dark toy fire hat of FIG. 1; and,

FIG. 8 is a left rear side perspective view of the glow-in-the-dark toy fire hat of FIG. 1.
